Primary Examiner — Marianne Pandozzi*Assistant Examiner* — Jae Liang(74) *Attorney, Agent, or Firm* — Kolisch Hartwell, P.C.**(57) CLAIM**

I claim the ornamental design for a growler, as shown and described.

DESCRIPTION

FIG. 1 is a left side elevational view of a growler showing my new design; the right side elevational view being a mirror image thereof,

FIG. 2 is a top plan view thereof.

The dashed lines shown in the drawings depict portions of the growler that form no part of the claimed design.
